United States Patent Office.

CHARLES E. BLIVEN, OF TOLEDO, OHIO.

Letters Patent No. 101,219, dated March 29, 1870.

IMPROVED BRACKET-HANGER.

The Schedule referred to in these Letters Patent and making part of the same

To all whom it may concern:

Be it known that I, CHARLES E. BLIVEN, of Toledo, in the county of Lucas and State of Ohio, have invented a new and useful Improvement in Bracket-Hangers; and I do hereby declare the following to be a full, clear, and exact description of the same, reference being had to the accompanying drawings, in which—

Figure 1 is a perspective view of my invention.

Figures 2 and 3 represent different arrangements of the same.

My invention consists in constructing bracket-hangers with horizontal and transverse bolt-slots, for the purpose of facilitating original adjustment in either horizontal or vertical directions.

My invention is applicable to all classes of machinery where bracket-hangers are employed, but will be most widely useful perhaps as a curtain-fixture, and for that purpose it is specially adapted.

That others may fully understand its construction and use, I will particularly describe it.

The bearing or box is located at A, and in case it is intended to support shafting or other mechanism, a suitable box will be placed at that point; for many purposes, however, no separate box will be required.

In mounting hangers of any kind, adjustments are always necessary, and in the use of bracket-hangers these adjustments are sometimes required in a vertical and sometimes in a lateral direction.

In the matter of curtain-fixtures the adjustment is generally vertical, to secure a level position for the roller.

To secure facility for both the adjustments named, I provide the horizontal slot B and the vertical slot C.

When the bracket is being set, if the required adjustment will be in a vertical direction, then the first bolt is inserted in the vertical slot C, and "set up" sufficiently tight to hold the bracket while the adjustment is being effected. Another bolt is then inserted through the horizontal slot B, and the operation is perfected. When the adjustment is lateral, then the proceeding is the reverse of that named.

In putting up hangers of this description, the first bolt should be put through the horizontal slot of one and the vertical slot of the other, and one bracket may then be moved for vertical adjustment and the other for horizontal adjustment.

Having described my invention,

What I claim as new is—

The bracket-hanger, constructed with horizontal and vertical slots B C, substantially as and for the purpose set forth.

CHARLES E. BLIVEN
